United States Patent Office

THOMAS WILES, OF INDIANAPOLIS, INDIANA.

Letters Patent No. 72,577, dated December 24, 1867.

IMPROVEMENT IN JACKS.

The Schedule referred to in these Letters Patent and making part of the same.

TO ALL WHOM IT MAY CONCERN:

Be it known that I, THOMAS WILES, of Indianapolis, in the county of Marion, and State of Indiana, have invented a new and useful Improvement on Jacks; and I do hereby declare that the following is a full, clear, and exact description thereof, reference being had to the accompanying drawings, and to the letters of reference marked thereon.

Figure 1 represents a perspective view, and

Figure 2 a section.

The nature of my invention consists in constructing a box, A, with a closed side and bottom, H G. The top, F, is partly closed, so as to permit the jack D to pass through it. The opposite side to H is open for the lever B to work in. This lever B rests on the fulcrum C, and bears very large leverage placed upon the jack D. On the opposite side is the check E fastened to the box at I. The red lines on drawings indicate how the jack works. I can raise an immense weight with my jack, and produce one for a very limited sum of money. It is handy, easily transported, and does not get out of order.

What I claim as my invention, and desire to secure by Letters Patent of the United States, is—

The combination of the box A with the lever B, fulcrum C, jack D, and check E, applied to a lever-jack.

THOMAS WILES.
